US00D802055S

(12) **United States Design Patent** (10) Patent No.: **US D802,055 S**
Chen et al. (45) Date of Patent: ** Nov. 7, 2017

(54) **WIRELESS GAME CONTROLLER**

- (71) Applicant: **Oculus VR, LLC**, Menlo Park, CA (US)
(72) Inventors: **Yi-yaun Chen**, Seattle, WA (US); **Peter Wesley Bristol**, Seattle, WA (US); **Robert Bruce Hubler**, Woodinville, WA (US); **Quintin Morris**, Issaquah, WA (US)
(73) Assignee: **Oculus VR, LLC**, Menlo Park, CA (US)
(**) Term: **15 Years**
(21) Appl. No.: **29/571,027**
(22) Filed: **Jul. 13, 2016**

CLAIM

The ornamental design for a wireless game controller, as shown and described.

DESCRIPTION

FIG. 1 is a front isometric view of a wireless game controller showing the new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines indicate unclaimed subject matter and form no part of the claimed design.

1 Claim, 7 Drawing Sheets(56)
